OLIVE BROOKS, OF NEW YORK, N. Y.

WAISTBAND

Application filed August 7, 1929. Serial No. 384,040.

This invention relates to waistbands such as used around the bottoms of women's blouses and the tops of pajamas, and women's underwear such for example as step-ins, pants, bloomers, etc.

At present the waistbands used in such garments consist of a continuous circular strip of rubber elastic fabric sewed together at its ends and enclosed within a casing or hem around the edge of the garment. The elastic material used, particularly in the medium priced and cheaper grades of garments, is too tight to be worn comfortably when new, or becomes so after the first or second washing because of shrinkage in the elastic. The wearer must either endure the discomfort, lengthen the waistband by piecing, or insert an entirely new waistband.

Moreover, rubber elastic fabric of any kind, and particularly in the cheaper grades, loses its strength long before the rest of the garment is worn out, so that even when the original waistband is of good quality elastic, the wearer may be forced to insert at least one, or more often two or three new waistbands during the life of the garment. This is a petty sewing task too small to take to the dressmaker, but it has to be done so frequently that it is a thoroughgoing nuisance. When the elastic first begins to lose its strength, the waistband may be shortened by means of a tuck, fastening it either by sewing or by the use of a safety pin, or it may simply be cut and tied together in a knot, or a loop formed and knotted, without cutting. But these are all makeshifts, and with the light clothing which women usually wear, such tucks, loops or knots are very apt to show through the clothing.

The present invention aims to do away with these discomforts and to provide a waistband which is readily replaceable in the garment in a moment's time.

The object of the invention also is to provide an elastic waistband which can be quickly inserted in the casing of a garment and which is capable of adjustment to the correct size both before and after insertion.

The invention will be understood by re-

ferring to the accompanying drawings in which

Fig. 1 is a perspective view of my improved waistband,

Figs. 2 and 3 are slightly enlarged views of the clasp, Fig. 2 being a section taken on line 2—2 of Fig. 3 and Fig. 3 being a section taken on line 3—3 of Fig. 2,

Fig. 4 is a perspective view showing the manner of opening the clasp and joining it with the opposite end of the waistband,

Fig. 5 is a perspective view of the upper portion of a pair of bloomers or pants with the improved waistband inserted therein, and

Fig. 6 is a sectional view illustrating the use of the elongated clasp as a bodkin.

Referring now to these drawings, the waistband comprises a strip 10 preferably of elastic material, and usually of elastic webbing in which the elastic properties are imparted thereto by weaving cords of india rubber into the webbing. The strip is usually about one quarter of an inch in width and has at one end an elongated clasp 11, and at the other end a loop 12 is formed in the strip for engagement with the clasp, the loop preferably being adjustable in length so as to vary the girth of the waistband.

The clasp 11 consists of an oblong eye of thin stiff material, no wider than the strip than necessary for the requisite strength and stiffness, and of sufficient length to take the place of a bodkin or shirring needle in running the waistband through the casing of the garment to which it is to be applied. The clasp preferably has two substantially parallel arms 13 extending in the direction of the waistband at each side of the strip 10 and joined together at the rear end of the clasp by a crossbar 14, by means of which the clasp is permanently fixed to the end of the waistband by stitching 15.

The outer ends of the side arms 13 are formed with overlapping fingers 16 which lie crosswise of the clasp about parallel to the rear bar 14. The fingers 16 in the normal position of the clasp overlie one another in close contact but they may be separated laterally by the fingers, as illustrated in Fig. 4, so that

the loop 12 may be placed over one of the fingers 16 and beneath the other, whereafter the fingers are allowed to spring to their normal position and the loop 12 is firmly secured 5 to the clasp as indicated in Figs. 1, 2 and 3.

Although the material of the clasp is comparatively stiff, so that the clasp will serve well as a bodkin, nevertheless it is sufficiently yielding or flexible to permit the fingers 16 10 to be readily separated to receive the loop 12. The clasp may be made of metal, celluloid, or other suitable material possessing the desired strength, stiffness, and yielding or resilient properties. The clasp is preferably made in 15 thin flat form as shown more particularly in Figs. 2, 3 and 4 since in this way the thickness of the clasp is kept to a minimum, and the fingers 16 are given maximum strength to resist bending. It is important to avoid the 20 placing of anything at the waistline which will give the appearance of increasing the size of the waist, or which will indicate its presence through the outer clothing, and it will be seen by referring to Fig. 3 that when 25 the clasp is made of thin flat material the thickness of the waistband is not appreciably greater than the joints in the waistbands now in common use made by the overlapping and sewing together of the ends of the band.

Thus at the left of Fig. 3 it will be seen that the maximum thickness is caused by the three thicknesses of the strip 10 at the stitching 15, while at the right the maximum thickness is caused by two thicknesses of the strip 10 and the two overlapping fingers 16. The side arms 13 of the clasp and the fingers 16 are made flat and sufficiently thin so that the total thickness of the clasp and fabric at the right hand end is no greater than the total thickness of the clasp and fabric at the left hand end.

Referring now to Fig. 5, the waistband is shown inserted in position in the casing 17 formed by means of a hem or otherwise at the upper edge of a pair of bloomers or pants 18. It is customary to make the casing 17 either closed throughout its entire length or provided with a single slit or aperture 19. Accordingly the waistband is located in a 45 position where it is comparatively inaccessible. The end 20 of the portion of the strip 10 which forms the loop 12 is provided with an adjusting device consisting of a slide 21 provided with suitable arms or bars through 50 which the portion of strip 10 which forms the waistband proper passes in slidable frictional engagement. It will be understood that by grasping the slide 21 with the fingers it can be slid either to the right or left in Fig. 1 so as to either shorten or lengthen the girth of the waistband by increasing or diminishing the length of the loop 12.

The distance which it is necessary to move the slide 21 on the strip 10 is always twice as great as the change in girth of the waistband 55

effected thereby. Accordingly by placing marks such as the figures 27 and 29 on the outside of the strip 10 as shown in Fig. 1, the girth of the waistband is indicated in inches or other desired units, and the girth of the band can be accurately pre-set by adjusting the slide 21 with respect to these indicating numbers.

The method of using my improved waistband is as follows:

When a new garment is furnished with my improved waistband, if the size of the waistband is not correct, it is only necessary to pull out of the casing that part of the waistband carrying the slide 21 and lengthen 70 the band the desired amount. The facility with which the loop 12 may be removed from engagement with the clasp 11 permits this operation to be done very easily. In pulling the waistband part way out to shift the slide, 75 the clasp end of the band may tend to slip back into the casing. With the ordinary band this would be quite a great inconvenience as it would necessitate the use of a shirring needle or other bodkin device in order to run the entire band throughout the whole length of the casing. With my improved 80 waistband, however, the bodkin is always present and firmly attached to the end of the waistband in the form of the clasp 11 and if this clasp should happen to slip back into the casing for a few inches, it may be run back again very quickly, thus doing away with the pulling of the entire band from the casing and placing a bodkin upon it, and then running it again through the entire casing.

This procedure does away with the necessity of fumbling with the slide 21 while in the casing in an attempt to adjust the girth of the band without removing it from the casing. This is always difficult to accomplish because it is not easy to separate the two strips forming the loop when they are concealed and confined within the casing, and pull on the right one. Also the slide can only be moved a minute distance at a time because the casing will not stretch to any great extent.

When the elastic has shrunk to the point where it is uncomfortably tight, as it is apt to do after the first or second washing, it can be quickly and easily readjusted in length in the manner just described.

When a waistband is worn out, whether of the ordinary type or of my improved type, the old waistband is first removed from the casing 17. The slide 21 is then adjusted with respect to the indicating numerals on the band to the wearer's waist size. The waistband is then run into the casing clasp end first, the clasp being used to serve the purpose of a bodkin or runner. Then the clasp is opened as previously explained and as illustrated in Fig. 4 and the loop 12 on the other 110 115 120 125 130

end of the waistband is quickly attached to the clasp.

It will be understood that my improved belt or band may be used not only as a waistband, but also as knee bands for bloomers, and in fact the above is merely an exemplifying disclosure of one form of my improved waistband and clasp, and the invention extends to those constructions which come within the scope of the appended claims.

I claim:

1. A waistband comprising a thin flat strip of elastic material, an adjusting device permanently attached to one end of the strip and 5 slidably mounted on the strip near one end, the material of the strip between the adjusting device and the end of the band being bent upon itself to form a flat loop, and an elongated clasp of thin stiff resilient material 10 permanently attached to the opposite end of the band and having flattened ends turned crosswise to form a pair of thin flat overlapping fingers normally lying in contact with one another and separable to receive and 15 hold said loop, said clasp being sufficiently elongated to serve as a bodkin for inserting the belt in the casing of a garment.

2. A waistband comprising a thin flat strip of elastic material, one end of said strip being bent upon itself to form a flat loop, an elongated clasp of thin stiff resilient material 20 attached to the opposite end of said waistband and having flattened ends turned crosswise to form a pair of thin flat overlapping fingers 25 normally lying in contact with one another and separable to receive and hold said loop, said clasp being sufficiently elongated to serve as a bodkin for inserting the waistband in the casing of a garment, and means for adjusting the length of said waistband.

In testimony whereof I affix my signature.
OLIVE BROOKS.
